UNITED STATES PATENT OFFICE.

JOHN MONACELLI, OF MEDINA, NEW YORK.

PUNCH.

1,295,785.

Specification of Letters Patent.

Patented Feb. 25, 1919.

Application filed July 22, 1918. Serial No. 246,067.

To all whom it may concern:

Be it known that I, JOHN MONACELLI, a citizen of the United States, residing at Medina, in the county of Orleans and State 5 of New York, have invented new and useful Improvements in Punches, of which the following is a specification.

This invention relates to an improvement in centering punches.

10 The object of the invention is to provide a simple, inexpensive, and easily operated tool for center punching or marking the ends of rods, bars or the like preparatory to turning or drilling such bars, rods, etc.

15 In the drawings, accompanying this specification, like parts are indicated by corresponding reference characters throughout, and in which;

20 Figure 1 is a side elevation, partly in section of my improved centering tool.

Fig. 2 is an enlarged elevation, partly in section of the punch member for the tool.

The centering-tool proper consists of a hollow cone-shaped piece 5 having at its 25 reduced end an extension providing a neck 6. The neck from the outer end thereof is centrally formed with a longitudinal passage 7 that communicates with a larger passage which provides a pocket 8 for the removal 30 of the head 9 of the centering element.

The head 9 has its outer end pointed, being of a vertical formation and its inner end is provided with a threaded recess 10. The threads in this recess are engaged by the 35 threads on a reduced extension 11 of the shank 12 of the punch or tool. The shank 12 has its outer end integrally formed in an enlargement providing a head 13.

40 The bar or solid tubular member 14 is arranged in the hollow conical portion 5 of the device, contacting with the side walls thereof. A blow is delivered on the head 13 of the shank 12 forcing the punch member 9 in the direction of the bar 14 and the 45 pointed end 15 thereof against the inner end of the bar 14, thus centrally providing the bar or rod 14 with an indenture, and thus properly centering the bar or the like.

From the foregoing it is believed the simplicity and advantages of the construction 50 will be understood without further description. The shank 12 is freely movable through the passage 7 of the neck 6, and when in the position illustrated in Fig. 1 the head of the punch is wholly received in 55 the pocket 8. The weight of the punch will normally cause the head 13 to rest on the outer end of the neck 6. The tubular bar 14 when inserted in the hollow member 5 will contact with the pointed end 15 of the 60 punch. This will force the shank 12 outward of the neck 6, bringing the punch in a position to be contracted by a hammer or the like while at the same time, the member 14, engaging with the flared inner wall 65 of the member 5 will be properly positioned to be centered by the punch. The pointed end of the punch is, of course, more susceptible to wear than any other part thereof, and consequently I have made the portion 9 70 removable from the shank of the punch. By this arrangement worn points may be readily replaced. The head 13 limits the movement of the punch in one direction, and the member 9 limits the movement of the punch in an 75 opposite direction.

Having thus described the invention, what I claim is:

In a device for the purpose set forth, a hollow cone-shaped member having its reduced end formed with an extension providing a neck, said neck having a central passage therethrough and an enlarged pocket communicating with the passage at the juncture of the neck with the body of the 85 said member, a shank freely slidable through the passage in the neck, said shank having its outer end formed with a head and its inner end provided with a reduced threaded extension, and a pointed member having its 90 body provided with a threaded socket receiving the threaded extension of the shank, and said pointed member designed to be snugly received in the pocket of the shank.

In testimony whereof I affix my signature. 95
JOHN MONACELLI.
